UNITED STATES PATENT OFFICE.

JOHN A. JOHNSON, OF LOCKPORT, ILLINOIS, ASSIGNOR OF ONE-HALF TO ENOCH CARLSON, OF CHICAGO, ILLINOIS.

SASH LOCK AND LIFTER.

1,126,223.

Specification of Letters Patent.

Patented Jan. 26, 1915.

Application filed August 10, 1914. Serial No. 856,065.

To all whom it may concern:

Be it known that I, JOHN A. JOHNSON, a citizen of the United States, residing at Lockport, in the county of Will and State of Illinois, have invented certain new and useful Improvements in Sash Locks and Lifters, of which the following is a specification.

My invention is a combination sash lock and lifter and has for its object to provide an improved device for the locking of a window sash in position and for unlocking the same by the same movement which raises or lowers the sash.

15 A further object of my invention is to provide a new and improved structure and combination of parts to effect the object set forth.

In the accompanying drawings, Figure 1 is an elevation, partly sectional, of a window sash and frame showing my invention in place. Fig. 2 is a vertical section on the line 2—2 of Fig. 1. Fig. 3 is a sectional view showing the movable parts of my invention in the position which they occupy when the sash is locked. Fig. 4 is a similar view with the sash unlocked. Fig. 5 is a plan view of the parts in the position of Fig. 3. Fig. 6 is a similar view of the parts in the position of Fig. 4. Fig. 7 shows an alternative construction of the locking bolt.

In the embodiment of my invention illustrated herein, bolts 1 are held in a locked position by a locking lever 2 operating through reciprocating rods 3 and actuated by a spring 4; and are released from a locked position by means of a pivoted finger bar 5 acting through pins 6 and 7. The finger bar serves also as a catch or handle by which to raise and lower the sash. The reciprocating rods 3 and the bolts 1 are contained in a suitable bore in the window sash, and when in a locked position the bolts engage cam sockets 8 set at intervals in the stile or jamb of the window casing. A suitable plate 9 is attached to the sash at or near the middle and opposite the bore containing the rods 3 and is provided with lugs 10 perforated near their inner extremities for receiving the ends of the said rods. Upon a standard 11, mounted on the plate 9, is pivotally mounted the locking lever 2 which is actuated by the torsion spring 4 to rotate in the direction of the arrow shown

in Fig. 3. Compression springs 12 are connected with the heads of bolts 1 and bear against the lugs 10 so as to exert a constant outward pressure on the bolts 1.

The finger bar 5 is provided with stop shoulders 13 adapted to contact with the plates 9 as soon as the locking lever 2 has released the rods 3 and bolts 1.

In operation, assuming that the sash is closed in the position shown in Fig. 1 (when the lever 2 and pins 6 and 7 will be in the position shown in Fig. 3), the finger bar 5 is lifted, the immediate effect being to depress the pin 6 and rotate the lever 2, thus releasing both rods 3. The upper stop shoulder 13 then comes in contact with the plates 9, preventing further pivoting of the finger bar, and continued upward pressure on the finger bar serves to raise the sash, the bolts 1 being free to slip out of engagement with the curved sockets 8. When the sash has been raised to the desired height, the finger bar 5 is released. The bolts 1 are then held in engagement with a pair of the sockets 8, by the action of the compression spring 12, and the inner ends of the rods 3 are flush with the inner sides of the lugs 10, and the action of the spring 4 causes the lever 2 to rotate in the direction indicated by the arrow in Fig. 3 until stopped by the pins 6 and 7, when the ends of the lever are respectively opposed to the ends of the rods 3, thus locking the bolts securely in position. When it is desired to lower the sash, the finger bar 5 is depressed, and the pin 7 operates to rotate the lever 2 with the same effect of releasing the rods 3 and permitting the withdrawal of the bolts 1. The lower shoulder 13 then comes in contact with the plates 9, and continued pressure on the finger bar 5 brings the sash down to the desired position, when the finger bar is released and the locking action takes place as before.

In Figs. 1, 2 and 5, I have shown the locking bolts as made with a smooth rounded end. In the alternative construction shown in Fig. 7, a roller 14 is substituted for this construction, the operation being as above described. Other modifications of the structure may be made without departing from the spirit and scope of the invention.

I claim as my invention:

1. In a sash lock and lifter, spring-actuated bolts, a spring-actuated pivoted locking

lever, and a finger bar adapted to release said bolts by rotating said locking lever.

2. In a sash lock and lifter, spring-actuated bolts on opposite sides of the sash, 5 spring-actuated locking means normally operating to hold said bolts in a locked position, and a finger bar pivoted to said sash and operatively coacting with said locking means to withdraw the latter.

10 3. In a sash lock and lifter, in combination, bolts, a spring-actuated locking lever adapted to hold said bolts in a locked position, and a pivoted finger bar adapted to rotate said lever out of a locking position 15 when said finger bar is tilted upward or downward.

4. In a sash lock and lifter, in combination, spring-actuated bolts, a spring-actuated pivoted locking lever adapted to hold said 20 bolts in a locked position, and a finger bar having arms coacting respectively with the arms of said locking lever for rotating said lever out of a locking position when said finger bar is lifted or depressed.

25 5. In a sash lock and lifter, a pair of spring-actuated opposed reciprocating bolts having their proximate ends spaced apart; a locking lever adapted to be interposed in a direct line between said proximate ends; and

a finger bar pivoted to the sash for raising 30 or lowering the sash and simultaneously to rotate said locking lever to release said bolts.

6. In a sash lock and lifter, a plurality of cam sockets; a pair of spring-actuated bolts 35 adapted to engage with said sockets; a single pivoted spring-controlled locking lever adapted to lock said bolts in place; a pivoted finger bar adapted to raise or lower the sash; and two pins extending from said finger bar and bearing respectively on opposite sides of said locking lever, whereby said lever is held to an operative position when the finger bar is at rest and is rotated to release the bolts when the finger bar is either raised or depressed.

40 7. In a sash lock and lifter, a pair of spring-actuated bolts; a single pivoted spring-controlled locking lever for locking said bolts in place; and a pivoted finger bar 45 for raising or lowering the sash, said bar having arms coacting with said locking lever to unlock the same.

In testimony whereof, I hereunto set my hand in the presence of two witnesses.

JOHN A. JOHNSON.

In the presence of—

HARRY L. LARSEN,

GEORGE W. PILKINGTON.
